UNITED STATES PATENT OFFICE.

CHARLES A. CAMPBELL, OF BROOKLYN, NEW YORK.

DESIGN FOR A GAS-LAMP.

48,240.

Specification for Design.

Patented Dec. 7, 1915.

Application filed December 22, 1914. Serial No. 878,621. Term of patent 7 years.

To all whom it may concern:

Be it known that I, CHARLES A. CAMPBELL, a citizen of the United States, and a resident of the borough of Brooklyn, city of New York, county of Kings, and State of New York, have invented a new, original, and ornamental Design for a Gas-Lamp, of which the following is a specification, reference being had to the accompanying drawing, forming part thereof.

The figure is a perspective view of a gas lamp, showing my new design.

I claim:

The ornamental design for a gas lamp, as shown.

CHARLES A. CAMPBELL.

Witnesses:

PATRICK A. BOLGER,
ENDA TANNER.
